(57) **CLAIM**

The ornamental design for a kite, as shown and described herein.

DESCRIPTION

FIG. 1 is a perspective view of my kite; FIG. 2 is a front view thereof, the front view being similar to the rear view; FIG. 3 is a right side elevational view thereof, the right side view being similar to the left side view; FIG. 4 is a top view thereof; FIG. 5 is a bottom view thereof; FIG. 6 is a perspective view of an alternative embodiment of my kite; FIG. 7 is a front view of the alternative embodiment, the front view being similar to the rear view; FIG. 8 is a right side elevational view of the alternative embodiment, the right side view being similar to the left side view; FIG. 9 is a top view of the alternative embodiment; and, FIG. 10 is a bottom view of the alternative embodiment. The elements shown in broken lines are for illustrative purposes only and form no part of the claimed design.
